UNITED STATES PATENT OFFICE.

LEOPOLD DAHLSTROM, OF SANTA CLARA, CALIFORNIA, ASSIGNOR OF ONE-HALF TO ROBERT MENZEL, OF SAME PLACE.

VALVE MECHANISM FOR DOUBLE-ACTING PUMPS.

SPECIFICATION forming part of Letters Patent No. 439,480, dated October 28, 1890.

Application filed July 8, 1890. Serial No. 358,062. (No model.)

To all whom it may concern:

Be it known that I, LEOPOLD DAHLSTROM, a citizen of the United States, residing at Santa Clara, in the county of Santa Clara and State of California, have invented certain new and useful Improvements in Valve Mechanism for Double-Acting Pumps; and I do declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 of the drawings is a representation of my device in elevation. Fig. 2 is a vertical longitudinal section. Fig. 3 is a vertical transverse section. Fig. 4 is a detail view.

The invention relates to improvements in 20 valve mechanism for double-acting pumps; and it consists in the novel construction described in the following specification, and illustrated in the accompanying drawings.

In the drawings, A represents the valve-box and water-chambers, which are formed integral with or secured to the cylinder B, and consist of the upper section *a* and lower section *b*, secured together by suitable bolts. This box or chamber has communication with 30 each end of the pump-cylinder B by means of the passages C and C'.

D represents the supply inlet or opening leading into the chamber D', and E the discharge leading from the outlet-chamber E', 35 each of said openings being provided with a screw-thread to form suitable couplings.

The chamber D' is partially divided into two compartments or chambers *d* and *d'* by the ridge or projection *f* of the box or case, 40 each of these compartments or chambers having an upwardly-extending passage *g* *g'* leading, respectively, into the chambers or passages C and C'. In each of these upwardly-extending passages is seated a puppet-valve H H', consisting of the annular flanged central portion, the laterally-flanged downwardly-extended portion *h* *h'*, and the upwardly-extending lug *h''*.

The water-chamber E, located in the upper 50 section of the box or case, is partially divided into two compartments or chambers K K' by

means of the projecting ridge *k* of the box, and are provided with the downwardly-extending passages *i* *i'*, respectively, communicating with the chambers C C', respectively. 55 The passages *i* *i'* are through the hollow thimbles formed on the upper section, which extend down into the passages C C', as shown, said thimbles also serving to unite the sections firmly together. Centrally of these compartments K K' and communicating with each is the outlet E, hereinbefore referred to.

The passages *i* *i'*, which connect the chambers C C' with chambers K K', are respectively provided with puppet-valves L L', which 65 consist of the central annular flanged portion, the downwardly-extending lugs *l* *l'*, and the upwardly-extending lugs *m* *m'*, provided each with vertical bore or slot which receive the downwardly-projecting lugs *o* *o'* of the removable caps O O', such arrangement limiting the upward movement of the valves, their downward movement being limited by the centrally-flanged portion engaging a shoulder in the passage.

The operation is as follows: The forward stroke of the piston in cylinder B will cause a vacuum to be formed in the passage or chamber C, forcing water through the inlet D into the chamber *d*, opening the valve H, and into 80 the passage or chamber C leading into the cylinder. The reverse stroke of the piston will close the valve H, open the valve L, and force the water in chamber C into chamber K and into the discharge, at the same time forming 85 a vacuum in the chamber C', having communication with the opposite end of the cylinder, and forcing water through the inlet into chamber *d'*, opening valve H', and into chamber C'. The next forward stroke of the piston will close the valve H', open valve L', and force the water in chamber C' into chamber K' and into the discharge, at the same time operating the opposite set of valves, as first 90 described, this operation being repeated with 95 each forward and backward stroke of the piston.

Having described the invention, what I claim as new therein, and desire to secure by Letters Patent, is—

The herein-described valve mechanism for double-acting pumps, consisting of the box or

case formed in two sections, one of said sections having the inlet, the inlet-chambers, the water-passages C C', located on opposite sides and communicating, respectively, with opposite ends of the pump-cylinder, the passages connecting the inlet-chamber and the chambers C C', and the puppet-valves located one in each said passages, the other or opposite section having the outlet, the outlet-chambers, the removable plugs for said chambers, the thimbles extending into the passages C C' of the other section and uniting the two, the

passages through said thimbles into the outlet-chambers, and the puppet-valves, one in each said passages, the two sections being removably secured together, substantially as described. 15

In testimony whereof I affix my signature in presence of two witnesses.

LEOPOLD DAHLSTROM.
